The ornamental design for a housing for a portable radio, as shown and described.

DESCRIPTION

FIG. 1 is a front perspective view of an ornamental design for a housing for a portable radio;

FIG. 2 is a rear perspective view thereof;

FIG. 3 is a front view thereof;

FIG. 4 is a first side view thereof;

FIG. 5 is a second side view thereof;

FIG. 6 is a rear view thereof;

FIG. 7 is a top view thereof; and,

FIG. 8 is a bottom view thereof.

The broken lines shown in the figures that are immediately adjacent to the shaded areas and define unshaded regions represent the bounds of the claim, while all other broken lines are directed to portions of the housing for a portable radio that do not form a part of the claimed design. The broken lines form no part of the claimed design. The unshaded regions at the first and second sides that are defined by solid lines, and include broken line features, form no part of the claimed design.
